WATERPROOF PURSE

Joseph John Colletti, Saranac Lake, N. Y.

Application September 17, 1935, Serial No. 40,947

1 Claim. (Cl. 150—42)

This invention relates to waterproof purses such as are worn by persons in bathing.

The invention has for its object to provide an improved waterproof purse to be worn by a person when in bathing.

Referring to the accompanying drawing, in which similar letters of reference indicate like parts.

Figure 1, view of a waterproof purse constructed in accordance with this invention.

Figure 2 is a vertical section of the purse on the line 2—2 of Figure 1.

Figure 3 is a vertical section of the purse, showing it open.

Figure 4 is a plan view of the top of the purse showing it closed.

Figure 5 is a plan view of the top of the purse showing it open.

1 indicates the purse which may be made entirely of rubber, or rubber-coated on the inside with an artificial leather covering on the outside.

To make the purse impervious to water, it is formed at its mouth with a waterproof lock, consisting of two rubber strips 2 and 3 located inside of the purse at its top, or open end, the strip 3 being formed with ribs 4, adapted to be moved into the grooves 5 of strip 2. The ribs 4 and grooves 5 are preferably curved as shown in dotted lines in Figure 1.

30 The strips 2 and 3 when moved together as shown in Figure 2, serve as a waterproof lock, being made of rubber, and by reason of the grooves and ribs being curved as shown in Figure 1, form an absolute waterproof lock, which is held tight by reason of the curved ribs and grooves.

To serve as additional security against the purse being accidentally opened, a non-rust metal fastener is provided, which consists of the strips 6 and 7, the strip 6 overlapping the strip 7 when the purse is closed. The strip 6 is provided with a button 11, which seats into the socket 12, thus

serving to lock the strips together as shown in Figure 2.

However, the fastener just described may be dispensed with, the lock formed by the strips 2 and 3 being sufficient to hold the purse tight in 5 closed position.

The strips 6 and 7 also serve as hand-holds to pull the purse open.

The ends of the strips 2 and 3 are sealed in any suitable manner to prevent water entering into 10 the purse, when the latter is closed.

The purse is employed to carry money, valuables and other necessary articles safely while in bathing.

15 The purse is secured to the body of the bather by means of a belt which passes through slots at the sides of the purse, as shown in Figure 1, the strips 8 at the sides of the purse, each having a slot 9, through which passes a belt 10, partly 20 shown in Figure 1.

The rubber strips 2 and 3, being elastic, when the purse is opened by pulling the hand holds 6 and 7, the mouth of the purse is brought to the bowed position shown in Figure 5.

25 When the non-rust metal fastener is dispensed with, the purse may be opened by squeezing the sides of the purse at its mouth, which brings the mouth of the purse to the bowed position shown in Figure 5, and on releasing the sides of the 30 purse at its mouth, the strips 2 and 3 snap together, forcing ribs 4 and grooves 5 into interlocked position.

I claim:

35 A waterproof purse, consisting of a pouch of waterproof material, having its mouth provided with a waterproof lock formed of a pair of resilient strips having interlocking ribs and grooves, said interlocking ribs and grooves gently curving through their entire interlocking lengths. 40

JOSEPH JOHN COLLETTI.
